UNITED STATES PATENT OFFICE.

JOHN F. KITZROW, OF KENOSHA, WISCONSIN.

RADIATOR ATTACHMENT.

1,125,120.

Specification of Letters Patent.

Patented Jan. 19, 1915.

Application filed March 30, 1914. Serial No. 828,335.

To all whom it may concern:

Be it known that I, JOHN F. KITZROW, a citizen of the United States, and resident of Kenosha, in the county of Kenosha and State 5 of Wisconsin, have invented certain new and useful Improvements in Radiator Attachments; and I do hereby declare that the following is a full, clear, and exact description thereof.

10 My invention consists in what is herein particularly set forth with reference to the accompanying drawings and pointed out in the claim of this specification, its object being to provide simple, economical, efficient 15 and sanitary means for connection with steam or hot-water heating radiators to supply moisture to atmosphere in apartments heated by said radiators and for collecting dust particles floating in said apartments.

20 Figure 1 of the drawings represent a perspective view of air-moistening apparatus in accordance with my invention partly broken away and applied to a radiator of which a fragment is shown; Fig. 2, a partly 25 sectional view of said apparatus and radiator; Fig. 3, a front elevation of a fragment of a wick element of the apparatus having a flexible support adjustable on an anchor-rod longitudinally of the same, and Fig. 4, a 30 perspective view illustrating a wick having another form of flexible support.

Referring by numerals to the drawings, 5 indicates a fragment of a steam or hot-water heating radiator, 6 a comparatively 35 deep narrow water receptacle provided with hangers 7 by which to suspend it in connection with the radiator. Radiators being of various lengths, receptacles of corresponding length may be provided according to the 40 demands of the trade, although one or more receptacles of a standard length may be employed on a single radiator.

Supported in each water receptacle is an anchor-rod 8, and loose on the rod are ends 45 of flexible supports 9 for wicks 10 that extend upward from said receptacle to elevate the water therefrom by capillary attraction. The flexibly supported wicks are adjusted longitudinally of the anchor-rod to register

with the spaces between coils of the adjacent 50 radiator and they are bent at their upper ends to extend into said spaces.

In practice, the receptacle 6 is hung in rear of a radiator at a suitable distance below the upper ends of its coils, and the bending of the upper ends of the flexibly supported wicks between said coils may be such that said wicks are invisible from the front of said radiator. Due to evaporation of water from the wicks, the surrounding atmosphere is moistened, and the number of wicks to be employed may be indefinitely varied with respect to regulating the supply of moisture to said atmosphere. Dust particles floating in the atmosphere will be attracted to the moistening-apparatus, but when said wicks and their flexible supports become dirty they may be readily cleaned by boiling in water.

As shown in Figs. 1, 2 and 3, the flexible support for each wick may be a jacket of non-corrosive woven-wire having the lower end thereof extended from said wick and bent to have sliding fit on the anchor-rod, or each wick may have its individual anchor. 75 In Fig. 4, it is shown that the flexible support may be a flat strip 9' of non-corrosive metal having ears 9'' bent on the wick.

I claim:—

The combination of a steam or hot water 80 heating radiator having two or more vertical coils, a single water receptacle suspended in connection with the radiator below the upper ends of its coils, and one or more 85 wicks each having an independent flexible support that projects upward therewith from within said receptacle and is also bent therewith at the upper end between a pair of said coils.

In testimony that I claim the foregoing I 90 have hereunto set my hand at Kenosha in the county of Kenosha and State of Wisconsin in the presence of two witnesses.

JNO. F. KITZROW.

Witnesses:

R. M. REILLY,
H. J. WINSTEN.
